(57) **CLAIM**

The ornamental design for a charger with stabilizer, as shown and described.

DESCRIPTION

FIG. 1 is a front-bottom-left side perspective view of a charger with stabilizer of my new design;

FIG. 2 is a bottom view thereof;

FIG. 3 is a top view thereof;

FIG. 4 is a right side view thereof;

FIG. 5 is a left side view thereof;

FIG. 6 is a front view thereof;

FIG. 7 is a rear view thereof;

FIG. 8 is a second perspective view thereof;

FIG. 9 is a third perspective view thereof; and,

FIG. 10 is a fourth perspective view thereof.

The broken lines in the drawings are for the purpose of illustrating portions of the charger with stabilizer that form no part of the claimed design.

1 Claim, 5 Drawing Sheets
